Primary Examiner — Susan Bennett Hattan*Assistant Examiner* — Marie D. Fast Horse(74) *Attorney, Agent, or Firm* — Rosenberg, Klein & Lee(57) **CLAIM**

The ornamental design for a portable storage device, as shown and described.

DESCRIPTION

FIG. 1 is a front perspective view of a portable storage device, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the figures show portions of the portable storage device that form no part of the claimed design.
